UNITED STATES PATENT OFFICE.

EARL M. STERRY, OF BUFORD, COLORADO.

PLOWING-MACHINE.

1,309,969.

Specification of Letters Patent. Patented July 15, 1919.

Application filed January 30, 1919. Serial No. 273,979.

To all whom it may concern:

Be it known that I, EARL M. STERRY, a citizen of the United States, residing at Buford, in the county of Rio Blanco and State of Colorado, have invented certain new and useful Improvements in Plowing-Machines, of which the following is a specification.

This invention relates to plows, and more especially to spaders; and one object of the device is to provide means for preventing the breaking of the shovels in case they strike a stone; another object is to provide means for converting the machine into a cultivator or a sage bush grubber.

Yet another object is to provide means for swinging the shovels out of position to engage the earth, as when the machine is to be moved from place to place.

Other objects will appear in the following specification and claims, and reference is made to the drawings, wherein:—

Figure 1 is a side elevation of this machine complete,

Fig. 2 is a plan view,

Fig. 3 is a cross section on the line 3—3 of Fig. 2,

Figs. 4 and 5 are vertical sectional details of the shovel standards in two positions,

Fig. 6 is a sectional detail of one of the bearings thereof,

Fig. 7 is a fragmentary detail of the pawl releasing mechanism.

Mounted on wheels 1 is a frame 2 carrying preferably a seat 3 and a motor 4 just in rear of the same, and the motor shaft is connected by sprockets and belt 5 with a crank shaft 6 having a plurality of oppositely disposed cranks as perhaps best seen in Fig. 2. This view shows but four of the cranks, but it will be understood that a greater number may be employed if desired.

The shaft is mounted in bearings 7 on the frame 2, and just inside of the same hangers 8 are also mounted on said shaft, their lower ends carrying a skeleton structure 10 which

supports a transverse dirt board 11 standing preferably between the rear wheels. From the structure 10 rods 12 rise into barrels 13 connected at their upper ends at 14 to the frame, and within these barrels are springs indicated at 15 so that the rods and barrels may telescope to a certain extent when the parts are connected as seen in Fig. 1. This

permits the entire skeleton structure to swing a little so that when the shovels (de-

scribed below) strike any hard obstruction they may yield upward and forward rather than being broken. Ropes 16 are also carried upward from said structure 10 and wound on drums 17 carried on a shaft 18 journaled in the frame, and one end of this shaft has a ratchet wheel 19 engaged by a finger 20 at the inner end of a pawl 21 which is fixed at 22 to the frame 2. The shaft 18 is fast through the ratchet, outside of which it carries a cam 25 underlying the pawl 21 as best seen in Fig. 7, and beyond the cam the shaft is cranked as seen at 26. The flat face of the cam is disposed toward the crank so that when the latter hangs pendant as seen in this view the finger is raised out of engagement with the ratchet wheel, but when the crank 26 is thrown up as seen in Fig. 1 the finger is allowed to engage the ratchet wheel. Thus when the parts stand normal, the rope 16 is not so fastened that it may not pay out in case the skeleton structure swings to the rear a little as permitted by the spring 15 in the barrel 13. When it is desired to swing this skeleton structure up under the frame and out of the way, as when the machine is to be transported from place to place, the barrel is disconnected at the point 14 from the frame 2 and the rope 16 wound upon the drum by means of the crank handle, the pawl finally coming to rest as shown in Fig. 1 so that the finger engages the ratchet wheel.

The hangers 8 support another crank shaft 36 whose cranks are equal in number and disposed in parallelism with those in the upper crank shaft 6. On each two superposed cranks is mounted a shovel standard 30 as best seen in Figs. 4 and 5. This standard is composed of a strip of metal bent into U form, its bend 31 passing over the upper crank 6 and a block 32 underlying this crank and making a complete bearing. The arms of the U-shaped strip passes astride the lower crank and a block 33 underlies it. Clips 34 connect the arms at several points, and bolts 35 connect them near their lower ends and clamp between them the shank 56 of a shovel whose blade is indicated at 37, the blade preferably standing slightly oblique to the shank. Finally, coiled expansive springs are interposed between the two bearings and between the lower bearing and the shank, as indicated by the numerals 38 and 39.

In order that the lower crank shaft may revolve simultaneously with the upper crank shaft, the two shafts are connected by sprocket wheels and a chain indicated broadly at 40, and in Fig. 3 two of these connecting elements are shown. Yet it is possible that, under the exigencies of a case and the stresses to which the machine is subjected, and especially in view of the fact that the several standards may flex a little within their length, the cranks will not always be in strict parallelism; and for the purpose of permitting parts to yield a little I interpose the expansive springs 38 and 39 above and below the intermediate bearing for the lower crank shaft in each standard. One end of the upper crank shaft is herein shown as carrying a fly wheel 41. The parts are illustrated in the drawings as they are set for producing spading, and the shovels revolve in the direction of the arrow indicated on Fig. 1 and of course will revolve faster than the wheels and at their lowest points will descend lower than the surface of the earth. If desired certain of the shovels may be removed from the standards so that the machine becomes a cultivator and will dig astride a row if it is guided accurately along the same. By reversing the shovels within the frame, the device may be used as a sage brush grubber; and by changing the shape of the blades many other uses can be given to the machine.

The foregoing description and the drawings have reference to what may be considered the preferred, or approved, form of my invention. It is to be understood that I may make such changes in construction and arrangement and combination of parts, materials, dimensions, et cetera, as may prove expedient and fall within the scope of the appended claims.

Having thus fully described my invention, what I claim as new and desire to secure by Letters Patent, is:—

1. In a spading plow, the combination with a frame mounted on wheels, and a motor on said frame; of a crank shaft mounted in bearings on the frame, a pair of hangers pendant from the crank shaft, a second crank shaft mounted in the hangers, connections between the shafts to cause them to rotate in unison, connections between the upper shaft and the motor, upright standards each having two bearings mounted on superposed cranks, and shovels at their lower ends.

2. In a spading plow, the combination with a frame mounted on wheels, and a motor on said frame; of a crank shaft mounted in bearings on the frame, a pair of hangers pendant from the crank shaft, a second crank shaft mounted in the hangers, connections between the shafts to cause them to

rotate in unison, connections between the upper shaft and the motor, a skeleton structure carried by the lower ends of said hangers, a dirt board carried by said structure, means for swinging said structure forward and backward, upright standards each having two bearings mounted on superposed cranks, and shovels at their lower ends.

3. In a spading plow, the combination with a frame mounted on wheels, a motor on the frame, a crank shaft journaled in the frame and connected with the motor, hangers pivoted on said shaft, a second crank shaft carried by the hangers, and a plurality of shovels whose standards are mounted on superposed cranks; of a skeleton structure carried by the lower ends of said hangers, a dirt board at the rear of said structure, rods rising from its front end and each entering a barrel, detachable connections between the barrel and frame, and a spring within the barrel for cushioning the movements of the rod, for the purpose set forth.

4. In a spading plow, the combination with a frame mounted on wheels, a motor on the frame, a crank shaft journaled in the frame and connected with the motor, hangers pivoted on said shaft, a second shaft carried by the hangers, and a plurality of shovels whose standards are mounted on superposed cranks; of a skeleton structure carried by the lower ends of said hangers, a dirt board at the rear end of said structure, rods rising from the forward portion of said structure, yielding connections between their upper ends and the frame, ropes rising from said structure, and a drum mounted on the frame for winding on said ropes, for the purpose set forth.

5. In a spading plow, the combination with a frame mounted on wheels, a motor on said frame, hangers pivotally supported from the frame, upper and lower parallel crank shafts mounted in said hangers, means for connecting the shafts to cause them to rotate in unison, connections between one shaft and said motor, and plows whose standards are mounted on superposed cranks; of a skeleton structure at the lower ends of said hangers, a dirt board carried by the rear portion of said structure, ropes leading from its front portion upward, a shaft on the frame having drums on which said ropes are wound, and means for locking this shaft against rotation, for the purpose set forth.

6. In a spading plow, the combination with a frame mounted on wheels and carrying a motor, a pair of hangers pivotally mounted on said frame, the spading mechanism supported by said hangers, and connections between said mechanism and motor; of telescopic members connecting the lower ends of the hangers with the frame, springs in said members for cushioning the move-

ments of the hangers forward and backward, and manually operable means for swinging the hangers and the spading mechanism upward under the frame when the 5 telescopic elements are detached therefrom.

7. In a spading plow, the combination with a pair of crank shafts and means for revolving them simultaneously and in unison; of a shovel whose standard embraces 10 like cranks on the two shafts, a bearing at one end of the standard on the upper shaft,

a shovel at the lower end of the standard, a bearing for the lower shaft at the mid-length of the standard, and springs above and below the last-named bearing, for the 15 purpose set forth.

In testimony whereof I affix my signature in presence of two witnesses.

EARL M. STERRY.
